(57) **CLAIM**

The ornamental design for a hydraulic fluid cleaning cart, as shown and described.

DESCRIPTION

FIG. 1 is a perspective drawing showing front, right side and top views of my new design for a hydraulic fluid-cleaning cart.

FIG. 2 is a perspective drawing showing front, left side and top views of my new design for a hydraulic fluid cleaning cart.

FIG. 3 is a perspective drawing showing rear, left side and top views of my new design for a hydraulic fluid-cleaning cart.

FIG. 4 is a perspective drawing showing rear, right side and top views of my new design for a hydraulic fluid-cleaning cart; and,

FIG. 5 is a perspective drawing showing the motor and filter manifold assembly removed from the cleaning cart.
